UNITED STATES PATENT OFFICE.

JAMES HIRST, OF MELROSE, MASSACHUSETTS, ASSIGNOR TO CHERNACK MANUFACTURING COMPANY, OF PAWTUCKET, RHODE ISLAND, A CORPORATION OF RHODE ISLAND.

WARP-DELIVERING MEANS FOR LOOMS.

1,312,847.

Specification of Letters Patent.

Patented Aug. 12, 1919.

Application filed September 30, 1916. Serial No. 123,154.

To all whom it may concern:

Be it known that I, JAMES HIRST, a citizen of Great Britain, residing at Melrose, in the county of Middlesex and State of Massachusetts, have invented new and useful Improvements in Warp-Delivering Means for Looms, of which the following is a specification.

The object of the present invention is to provide improved warp-delivering means for looms, particularly circular looms that weave tubular fabric.

It is desirable to maintain uniform tension on the several warp members as the latter are interwoven with the filling member or members, and this is especially so in the case of circular looms. Ordinarily looms for weaving flat sheet fabric are provided with rotatable warp beams on which the warp members are wound, and such warp beams are usually provided with band brakes or other friction devices arranged to resist unwinding movement to keep the warp members under tension. In such cases the tension of the individual warp members is not necessarily of the same degree in any two of them, which condition is due, to a great extent, to the fact that the warp members are wound upon themselves on the beam.

My present invention provides a warp-delivering apparatus comprising a creel from the spools of which the strands are let through guides, and around a tension drum, and thence through, under, or over other guides to the loom in which they serve as the warp members to be woven. The drum referred to is provided with braking means that maintains the necessary tension of the warp members in the loom and that performs the same function as the well known warp beam that is provided with a brake, but the tension drum of my invention accomplishes a result that the well known warp beam does not accomplish, that is, it makes the tension uniform as to the individual warp members.

I have stated that the present invention is designed especially for use in conjunction with circular looms, but it is nevertheless adapted to be used in conjunction with looms for weaving flat sheet fabric.

Of the accompanying drawings, which illustrate one form in which my present invention may be embodied:

Figure 1 represents an elevation, front or

rear, of a creel, a stand therefor, and means for equalizing the tension of the several strands. One of the brake drums is shown in section in this figure.

Fig. 2 represents a vertical section including the creel stand and the lower portion of the creel, and includes conventional representations of two circular looms taking warp members from the one warp-delivering apparatus.

Fig. 3 represents an elevation of a portion of a take-up device that engages the strands between the tension drum and the creel.

Fig. 4 represents an end elevation of the device shown by Fig. 3.

Fig. 5 represents a top plan view of a portion of a guiding device through which the strands are drawn after leaving the tension drum.

Fig. 6 represents a top plan view of a thread guide through which the strands pass from the creel to the tension drum.

The same reference characters indicate the same parts wherever they occur.

The circles A and B are conventional representations of circular looms. Their structural details are immaterial as far as the present invention is concerned, for anyone skilled in the art of circular looms will readily understand the adaptability thereto of the warp-delivering means hereinafter described. The spools of the creel are, in the present instance, arranged in two groups, those of one group being designated by reference letter a, and those of the other group by reference letter b. The strands or warp members that are drawn from the spools are indicated respectively at a' and b'. The spools are mounted upon spindles 10, and the latter are affixed to frame members 11. The paddles indicated at 12 are mounted upon rods 13 and are arranged to bear under gravity against the peripheries of the spools to exert a slight retarding action on the unwinding movement of the latter.

The creel is mounted upon a stand indicated as a whole at 14. The stand is provided with two thread-guides 15, 15, one for each group of spools. Each thread-guide consists of a metallic bar and is provided with a series of holes 15', one such hole being provided for each strand or warp member. From the thread-guides 15, 15 the warp members pass to a take-up de-

vice 16, preferably passing through another guide-bar 17 before reaching the take-up. The chief function of the guide-bar 17 is to gather the strands of the two groups together into a common plane so that the take-up device will have the same effect in both character and degree on the strands of both groups. Guide bar 17 is provided with suitable holes, one for each strand, to all intents and purposes like the holes 15' in the bars 15, 15.

The take-up device 16 comprises a horizontal bar 18, two swinging arms 19, 19 supporting the latter by its ends, a series of guide pins 20 carried by said bar, and a confining rod 21 arranged parallel to bar 18 and supported by ears 22 formed upon or attached to the latter. The ends of bar 18 are square, as indicated in Fig. 4, to facilitate rigid connection with the arms 19 so that the two arms and bar collectively form a rigid unit. This rigid unit is hung on pivots 23 and normally would hang in a perpendicular position, but is held out of perpendicular, as shown by Fig. 2, by the stretchers of the strands that pass from the guide bar 17 to the tension drum 25. Some of the strands, as *b'*, pass once around the drum 25 and thence to a guide 26, while others, as *a'*, may pass slightly more than once around the drum and thence to a similar guide 27 at the opposite side of the stand from the guide 26. It will be understood, however, that instead of the duplex arrangement shown, all the strands may pass through either one of the guides 26, 27, and thence to one loom instead of being divided to supply two looms. As the strands leave the guides 26 and 27 they pass under idle guide rolls 28, thence to guiding elements 29 of any form and arrangement suitable to guide them to the looms. For convenience of description the strands *b'* are shown as being conducted to loom B, and strands *a'* to loom A.

The tension drum 25 is provided with a smooth metallic surface, being preferably a shell made of thin sheet material. It is sustained, in the present instance, by brake drums 30, 30, one at each end, and said brake drums are keyed or otherwise affixed to shaft 31. This shaft is mounted in bearings 32 and is preferably provided with hand-wheels 33 whereby it may be turned to turn back the drum whenever it is necessary to unweave the fabric to correct defects. Each brake drum is engaged by a flexible brake band 34. The ends of each band are connected to tension rods 35, 35. These rods extend through fixtures 36 and are provided with helical compression springs 37 respectively, and with nuts 38 for holding said springs under compression. The shell of the drum, being made of thin sheet metal, might 65 be twisted or buckled by torsional stress if

the braking action were applied only to one end thereof, and so might maintain the same degree of tension on all the strands. It is for this reason that two brakes are provided as shown. The cylindricity of the drum is 70 preserved by reinforcing-disks (not shown) between its ends, said disks fitting the shaft 31. Thus the shell is prevented from being buckled or sprung by the tension of the strands. 75

The thread-guides 26 and 27 are preferably made according to the details shown by Fig. 5. Each guide comprises a horizontal bar 39, a series of guide pins 40, and a confining rod 41. The bar 39 is provided with ears 42 for holding the rod 41. The spaces 43, each of which is defined by two contiguous pins 40, and by bar 39 and rod 41, are the spaces through which the strands are passed individually. Rod 41 is detachable from ears 42, in order to enable the strands to be drawn in laterally instead of being threaded through the spaces 43; and after the strands have all been arranged in their respective places with the pins 40 separating them one from another, the confining rod 41 may be inserted endwise through the ears 42, one end of the rod being straight to permit such insertion. 85

The thread-guiding elements of the take-up 95 16 are, to all intents and purposes, like those of the guides 26 and 27. The strands are separated one from another by the pins 20 and pass through the spaces indicated at 44. 100

The function of the take-up 16 is to take up whatever slack may occur between the creel and the tension drum. For example, if it should be necessary to turn back the drum incidentally to correcting a defect in 105 the woven fabric, or for any other purpose, such turning back would produce slack between the drum and the creel. In such case the take-up, always tending to swing to a perpendicular position, would take up the 110 slack caused by the back returning, and would thereafter give up the slack when the strands are fed forward. The tension device does not necessarily occupy any predetermined angular position when the strands are 115 being fed forward, for its angular position would be determined by the degree of resistance to the unwinding of the spools. 120

I claim:

1. A warp delivering apparatus comprising a warp creel, a rotatable tension drum to and around which the strands from said creel pass, said strands being divided into groups after leaving the drum and the different groups being led away in different directions, and a brake arranged to retard the rotation of the drum. 125

2. A warp delivering apparatus comprising a stand, a warp creel mounted on said stand adapted to carry spools of warp 130

material, a guide having eyes through which the several warp strands are adapted to pass, a drum mounted on said stand in position to engage on its peripheral surface the warp strands passing from said guide, a brake arranged to retard the rotation of said drum, and a plurality of separate guides to each of which a portion of the warp strands pass from the drum, the strands passing 10 said separate guides being led to separate destinations.

3. A warp delivering apparatus comprising a stand adapted to be placed on the floor, a warp creel mounted on top of said stand adapted to carry spools of warp material, a guide beneath said creel having eyes through which the several warp strands are adapted to pass, a drum mounted on said stand beneath said guide 15 in position to engage on its peripheral surface warp strands passing from said guide, a brake arranged to retard the rotation of said drum, and a guide to which the warp strands pass from the drum and from which 20 they are led to their destination.

4. A warp delivering apparatus comprising a stand, a drum mounted rotatably in said stand, warp thread guides arranged in said stand below and on opposite sides 30 of said drum, a brake arranged to retard rotation of the drum, a warp thread guide on the stand above the drum, and a creel mounted on the stand carrying spools of warp material.

35 5. In a warp delivering apparatus, a stand, a tension drum supported rotatably by said stand, brake drums connected with the opposite ends of said tension drums, loaded brake bands passing around and bearing on said brake drums and anchored to parts of the stand, said tension drum being adapted to have warp threads wrapped around it, and guides through 40 which the strands pass in their course to 45 and away from the drum.

6. In a warp delivering apparatus, a stand, a tension drum supported rotatably by said stand, brake drums connected with the opposite ends of said tension drums, 50 loaded brake bands passing around and bearing on said brake drums and anchored to parts of the stand, said tension drum being adapted to have warp threads wrapped around it, and guides through 55 which the strands pass in their course to and away from the drum, one of said guides being movable and arranged to bear athwart the threads, whereby to take up and pay out automatically any slack in the threads.

60 7. In a warp delivering apparatus, a

stand, a tension drum supported rotatably by said stand, brake drums connected with the opposite ends of said tension drums, loaded brake bands passing around and bearing on said brake drums and anchored to parts of the stand, said tension drum being adapted to have warp threads wrapped around it, a creel supporting thread masses in position for threads to be led therefrom to the tension drum, and a 65 70 guide through which the threads pass on their way to said drum, said guide being movably mounted and arranged to bear athwart the threads, whereby to take up slack therein.

75 8. The combination of a plurality of looms, a warp-creel, an elongated rotary tension drum, the strands from said creel extending to said drum and around a substantial part of the periphery of the latter, each 80 of said strands having independent bearing on said periphery, said strands being divided into groups after leaving said drum and said groups extending to said looms respectively, and a brake arranged to act on 85 said drum.

9. In a warp delivering apparatus, a stand, a creel carrying spools of warp material, a tension drum mounted on said stand in position to receive on its periphery 90 the warp strands from said creel, a brake to retard rotation of said drum, and a yieldingly mounted take up between the creel and drum, having eyes to admit the several warp strands and separate them from one 95 another on their way to the drum.

10. In a warp delivering apparatus a thread-guiding element comprising a bar, pins on said bar in series, and a confining rod mounted detachably on said bar normally crossing said pins in substantial parallelism with the bar and forming the outer boundaries of the eyes defined between the pins and the bar.

11. In a warp delivering apparatus a 105 take up device constituted by a bar, arms pivotally mounted and connected to said bar whereby the latter is adapted to swing while bearing against a series of threads, pins projecting from said bar between which 110 such threads may pass, and by which the threads are kept apart from one another, and a confining rod detachably connected with said bar and normally arranged substantially parallel therewith across the pins 115 to confine the threads in the spaces between the pins.

In testimony whereof I have affixed my signature.

JAMES HIRST.
